(57) **ABSTRACT**

A new and distinct cultivar of *Helleborus* plant named 'HL 1026' characterized by its upright to somewhat outwardly spreading and mounded plant habit; vigorous growth habit; dark green-colored leaflets with lighter green-colored venation; freely flowering habit; purplish red-colored flowers; and good garden performance.

2 Drawing Sheets

1

Botanical designation: *Helleborus niger* X *Helleborus x hybridus*.

Cultivar denomination: 'HL 1026'.

STATEMENT REGARDING PRIOR
DISCLOSURES BY INVENTOR/APPLICANT

An European Community Plant Breeder's Rights application for the instant plant was filed by the Inventor/ Applicant, Mr. Josef Heuger of Glandorf, Germany, on Dec. 1, 2022, application number 2022/2757. Foreign priority is not claimed to this application.

The Inventor/Applicant asserts that no publications nor advertisements relating to sales, offers for sale or public distribution occurred more than one year prior to the effective filing date of this application. Any information about the claimed plant would have been obtained from a direct or indirect disclosure from the Inventor or Applicant. Inventor/ Applicant claims a prior art exception under 35 U.S.C. 102(b)(1) for disclosure and/or sales prior to the filing date but less than one year prior to the effective filing date.

BACKGROUND OF THE INVENTION

The present invention relates to a new and distinct cultivar of *Helleborus* plant, botanically known as *Helleborus niger* X *Helleborus x hybridus* and hereinafter referred to by the name 'HL 1026'.

The new *Helleborus* plant is a product of a planned breeding program conducted by the Inventor in Glandorf, Germany. The objective of the breeding program was to create new uniform *Helleborus* plants with unique and attractive plant habit, leaf and flower coloration and tolerance to biotic and abiotic stresses.

The new *Helleborus* plant originated from a cross-pollination conducted by the Inventor in Glandorf, Germany in November, 2015 of a proprietary selection of *Helleborus*

niger identified as code number P628, not patented, as the female, or seed, parent and a proprietary selection of *Helleborus x hybridus* identified as code number O1687, not patented, as the male, or pollen, parent. The new *Helleborus* plant was discovered and selected by the Inventor as a single flowering plant from within the progeny of the stated cross-pollination grown in a controlled greenhouse environment in Glandorf, Germany in December, 2017.

Asexual reproduction of the new *Helleborus* plant by in vitro axillary meristem culture in a controlled environment in Glandorf, Germany since April, 2018 has shown that the unique features of this new *Helleborus* plant are stable and reproduced true to type in successive generations.

2

Plants of the new *Helleborus* have not been observed under all possible combinations of environmental conditions and cultural practices. The phenotype may vary somewhat with variations in environmental conditions such as temperature and light intensity without, however, any variance in genotype.

The following traits have been repeatedly observed and are determined to be the unique characteristics of 'HL 1026'. These characteristics in combination distinguish 'HL 1026' as a new and distinct *Helleborus* plant:

1. Upright to somewhat outwardly spreading and mounded plant habit.
2. Vigorous growth habit.
3. Dark green-colored leaflets with lighter green-colored venation.
4. Freely flowering habit.
5. Purplish red-colored flowers.
6. Good garden performance.

Plants of the new *Helleborus* differ from plants of the female parent selection in the following characteristics:

1. Leaflets of plants of the new *Helleborus* are darker green in color than leaflets of plants of the female parent selection.

2. Flowers of plants of the new *Helleborus* are darker purplish red in color than flowers of plants of the female parent selection. 5

Plants of the new *Helleborus* differ from plants of the male parent selection in the following characteristics:

1. Leaflets of plants of the new *Helleborus* are darker green in color than leaflets of plants of the male parent 10 selection.

2. Flowers of plants of the new *Helleborus* are lighter purplish red in color than flowers of plants of the male parent selection.

Plants of the new *Helleborus* can also be compared to 15 plants of *Helleborus niger* 'COSEH 1000', disclosed in U.S. Plant Pat. No. 25,316. In side-by-side comparisons, plants of the new *Helleborus* differ primarily from plants of 'COSEH 1000' in the following characteristics:

1. Plants of the new *Helleborus* have larger leaves than 20 plants of 'COSEH 1000'.

2. Plants of the new *Helleborus* have larger flowers than 25 plants of 'COSEH 1000'.

3. Flowers of plants of the new *Helleborus* are purplish red in color whereas flowers of plants of 'COSEH 1000' are white in color.

BRIEF DESCRIPTION OF THE PHOTOGRAPHS

The accompanying colored photographs illustrate the 30 overall appearance of the new *Helleborus* plant showing the colors as true as it is reasonably possible to obtain in colored reproductions of this type. Colors in the photographs may differ slightly from the color values cited in the detailed botanical description which accurately describe the colors of 35 the new *Helleborus* plant.

The photograph on the first sheet (FIG. 1) is a side perspective view of a typical flowering plant of 'HL 1026' grown in a container.

The photograph on the second sheet (FIG. 2) is a close-up 40 view of a typical flower of 'HL 1026'.

DETAILED BOTANICAL DESCRIPTION

The aforementioned photographs and following observations, measurements and values describe plants grown during the early spring in 17-cm containers in a glass-covered greenhouse in Glandorf, Germany and under cultural practices typical of commercial *Helleborus* production. During the production of the plants, day temperatures ranged from 12C to 32C and night temperatures ranged from 5C to 12C. Plants were 48 weeks old when the photographs were taken and 14 months old when the description was taken. In the following description, color references are made to The Royal Horticultural Society Colour Chart, 2015 Edition, 45 except where general terms of ordinary dictionary significance are used.

Botanical classification: *Helleborus niger* X *Helleborus x hybridus* 'HL 1026'.

Parentage:

Female, or seed, parent.—Proprietary selection of *Helleborus niger* identified as code number P628, not 50 patented.

Male, or pollen, parent.—Proprietary selection of *Helleborus x hybridus* identified as code number O1687, 55 not patented.

Propagation:

Type.—In vitro axillary meristem culture.

Time to initiate roots, winter.—About 55 days at temperatures about 12C.

Time to produce a rooted young plant, winter.—About 170 days at temperatures ranging from about 4C to 15C.

Root description.—Thick to thin, fleshy; typically white to brownish in color, actual color of the roots is dependent on substrate composition, water quality, fertilizer type and formulation, substrate temperature and physiological age of roots.

Rooting habit.—Low branching; sparse.

Plant description:

Plant and growth habit.—Herbaceous perennial; upright to somewhat outwardly spreading and mounding plant habit with flowers held within to above the foliar plane; plant shape, inverted triangular; vigorous growth habit and moderate to rapid growth rate.

Plant height, soil level to top of foliar plane.—About 36.5 cm.

Plant height, soil level to top of flowers.—About 48.8 cm.

Plant diameter (area of spread).—About 54.2 cm.

Leaf description:

Arrangement.—Leaves arranged in a basal rosette; leaves palmately compound with typically five leaflets per leaf.

Leaf length.—About 19 cm.

Leaf width.—About 20.4 cm.

Leaflet length.—About 12.7 cm.

Leaflet width.—About 6.1 cm.

Leaf shape.—Palmate; roughly reniform in outline.

Leaflet shape.—Elliptic, broadly elliptic or obovate.

Leaflet apex.—Acute.

Leaflet base.—Attenuate.

Leaflet margin.—Serrate; moderately coarsely undulate.

Leaflet texture and luster, upper surface.—Smooth, glabrous; coriaceous and tough; moderately glossy.

Leaflet texture and luster, lower surface.—Smooth, glabrous; coriaceous and tough; slightly glossy.

Leaflet venation pattern.—Pinnate and reticulate.

Leaflet color.—Developing leaflets, upper surface: Close to NN137A; midvein, proximally, close to 187A. Developing leaflets, lower surface: Close to 146A; midvein, close to N186C. Fully developed leaflets, upper surface: Slightly darker than a blend of 139A and 147A; at the base, tinged with close to N186C; venation, close to 144A. Fully developed leaflets, lower surface: Close to 147B; venation, close to N144C.

Petioles.—Length: About 12.7 cm. Diameter: About 6 mm by 7 mm. Strength: Strong. Texture and luster, upper and lower surfaces: Smooth, glabrous; slightly glossy. Color, upper and lower surfaces: Close to 144B; sparsely covered with fine dots and stripes, close to 197B.

Flower description:

Flower shape and habit.—Single rotate bowl-shaped flowers arranged in panicles; freely flowering habit with about three to five flowers per inflorescence and about 50 flowers and flower buds per plant; flowers face mostly outwardly and slightly nodding.

Fragrance.—None detected.

Natural flowering season.—Plants begin flowering about ten months after planting; plants flower naturally from late winter into the spring in Germany.

Flower longevity on the plant.—About ten days; sepals 5 persistent, other flower parts are not persistent.

Flower buds.—Length: About 2.6 cm. Diameter: About 1.6 cm. Shape: Broadly ovate to oblong. Texture and luster: Smooth, glabrous; matte. Color: Close to N186C; towards the apex, close to 187B.

10

Inflorescence height (including peduncle).—About 45.3 cm.

Inflorescence diameter.—About 18.2 cm.

Flower diameter.—About 7.1 cm.

Flower depth.—About 2.6 cm.

15

Petals.—All petals are transformed into nectaries.

Sepals.—Quantity and arrangement: About five arranged in a single whorl. Length: About 4 cm. Width: About 3.2 cm. Shape: Broadly ovate; slightly concave. Apex: Broadly and bluntly acute to close to 20 obtuse. Base: Truncate to obtuse. Margin: Entire; not undulate. Texture and luster, upper surface: Smooth, glabrous; matte to slightly glossy. Texture and luster, lower surface: Smooth, glabrous; slightly glossy. Color: When opening, upper and lower surfaces: 25 Close to 187B and 187C. Fully opened, upper surface: Close to 187C; at the base, close to 146C; venation, similar to lamina colors; color does not change with subsequent development. Fully opened, lower surface: Close to 187C; towards the margins 30 and apex, close to 187B; venation, close to 187A; color does not change with subsequent development.

Flower bracts.—Quantity per flower: Typically one.

Length: About 6.7 cm. Width: About 3.9 cm. Shape: 35 Ovate. Apex: Narrowly acute or cleft with three acute tips. Base: Truncate to cuneate. Margin: Mostly entire; distally, finely serrate; coarsely undulate. Color, upper surface: Close to 137A; towards the base, close to 146B; midvein, proximally, tinged with close to 187A and 187B. Color, lower surface: 40 Close to 147B; midvein, close to N186C.

Peduncles.—Length: About 35.1 cm. Diameter: About 5.5 mm to 6 mm. Aspect: About 15 degrees from vertical. Strength: Strong. Texture and luster: Smooth, glabrous; slightly to moderately glossy. 45 Color: Close to 146D; heavily covered with fine dots, close to 183A and 187A.

Pedicels.—Length: About 2.2 cm. Diameter: About 2 mm. Aspect: About 45 degrees from peduncle axis. Strength: Moderately strong. Texture and luster: 50

Smooth, glabrous; glossy. Color: Close to a blend of N186B and N186C; moderately covered with fine dots, close to 186D.

Reproductive organs.—Stamens: Quantity per flower: About 60. Filament length: About 1.3 cm. Filament color: Close to 186D; distally, close to 155A. Anther shape: Double and broadly reniform; basifixated. Anther size: About 1.75 mm by 2.5 mm. Anther color: Close to 154D. Pollen amount: Sparse. Pollen color: Close to 4D to lighter than 4D. Pistils: Quantity per flower: About seven to nine. Pistil length: About 1.1 cm. Stigma diameter: About 0.3 mm. Stigma shape: Club-shaped. Stigma color: Close to 156A. Style length: About 1.05 cm. Style color: Close to N186A. Ovary color: Close to N186C. Nectaries (transformed petals): Quantity per flower: About 11 to 14. Length: About 1.3 cm. Diameter: About 5 mm. Shape: Tubular, flattened; apices, obtuse. Texture and luster, inner and outer surfaces: Smooth, glabrous; slightly glossy. Color, immature, inner surface: Close to N144A; towards the apex, close to 183D. Color, immature, outer surface: Close to N144A; towards the apex, close to 183D; at the base, close to 200B. Color, mature, inner surface: Close to 151A; distally, close to 183A; venation, similar to lamina colors; with subsequent development, color becoming closer to a blend of 166A and 183A, and proximally, closer to 152D. Color, mature, outer surface: Close to 151A; distally, close to 183A; at the base, close to 200B; venation, similar to lamina colors; with subsequent development, color becoming closer to a blend of 166A and 183A, proximally, closer to 152D and at the base, close to 200B. Seeds and fruits: To date, seed and fruit development have not been observed on plants of the new *Helleborus*.

Garden performance: Plants of the new *Helleborus* have been observed to have good garden performance and to tolerate rain, wind, high temperatures about 35C and to be suitable for USDA Hardiness Zones 5 through 9.

Pathogen & pest resistance: To date, plants of the new *Helleborus* have not been observed to be resistant to pathogens and pests common to *Helleborus* plants.

It is claimed:

1. A new and distinct *Helleborus* plant named 'HL 1026' as illustrated and described.
